UNITED STATES PATENT OFFICE.

CHRISTOPHER RICHARDSON, OF NEWARK, NEW JERSEY.

DESIGN FOR A CARVING-FORK.

SPECIFICATION forming part of Design No. 28,444, dated April 5, 1898.

Application filed October 6, 1897. Serial No. 654,300. Term of patent 14 years.

To all whom it may concern:

Be it known that I, CHRISTOPHER RICHARDSON, a citizen of the United States, residing at Newark, county of Essex, State of New Jersey, have invented and produced a new and original Design for a Carving-Fork with Auxiliary Tine, fully described and represented in the following specification and the accompanying drawings, forming a part of the same.

My invention relates to a design for a three-tine carving-fork.

In the drawings illustrating this design, Figure 1 is a view of the carving-fork, showing the upper sides of the tines; and Fig. 2 is an edge view of the tines and part of the shank.

In my design the fork has lateral tines with a central tine of less length bent into a plane outside of and substantially parallel to the plane of the lateral tines.

A designates the lateral tines, and B the central tine connected to the bases of the lateral tines by the bent portion designated B' in Fig. 2.

The central tine B is shorter than the lateral tines A, as shown in the drawings.

The leading feature of my design for a fork of three tines is the form of the central tine, substantially as shown and described.

What I claim is—

The design for a carving-fork as herein described and shown.

In testimony whereof I have hereunto set my hand in the presence of two subscribing witnesses.

CHRISTOPHER RICHARDSON.

Witnesses:

L. LEE,
THOMAS S. CRANE.
